(57) **CLAIM**

The ornamental design for a platform for exercise apparatus, as shown and described herein.

DESCRIPTION

FIG. 1 is a front perspective view of a platform for exercise apparatus showing our new design;

FIG. 2 is a front view thereof;

FIG. 3 is a rear view thereof;

FIG. 4 is a top view thereof;

FIG. 5 is a bottom view thereof;

FIG. 6 is a first side view thereof;

FIG. 7 is a second side view thereof; and,

FIG. 8 is a front perspective view, showing the platform for exercise apparatus in use.

The portions of the platform for exercise apparatus shown in broken lines form no part of the claimed design.

The broken lines shown in FIG. 8 depict the environment and form no part of the claimed design.

1 Claim, 8 Drawing Sheets
